US00D807338S

(12) **United States Design Patent** (10) **Patent No.:** **US D807,338 S**
(45) **Date of Patent:** **** Jan. 9, 2018**

(54) **CASE FOR ELECTRONIC DEVICE**

(71) Applicant: **Dae-Young Kim**, Seoul (KR)

(72) Inventor: **Dae-Young Kim**, Seoul (KR)

(73) Assignee: **SPIGEN KOREA CO., LTD.**,
Geumcheon-Gu, Seoul (KR)

(**) Term: **15 Years**

(21) Appl. No.: **29/593,707**

(22) Filed: **Feb. 10, 2017**

Related U.S. Application Data

(63) Continuation of application No. 29/568,017, filed on Jun. 14, 2016, now Pat. No. Des. 788,760, which is a continuation of application No. 29/495,236, filed on Jun. 27, 2014, now Pat. No. Des. 771,607, application No. 29/593,707, which is a continuation of application No. 29/568,020, filed on Jun. 14, 2016, now Pat. No. Des. 791,116, application No. 29/593,707, which is a continuation of application No. 29/568,021, filed on Jun. 14, 2016, now Pat. No. Des. 786,233.

(57) **CLAIM**

The ornamental design for a case for electronic device, as shown and described.

DESCRIPTION

FIG. 1 is a front perspective view of a case for electronic device showing my new design;

FIG. 2 is another front perspective view thereof;

FIG. 3 is a rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines depict of unclaimed environment and form no part of the claimed design.

1 Claim, 9 Drawing Sheets
